BY Walker ATTY'S.

UNITED STATES PATENT OFFICE.

DAVID WALKER, OF NEWARK, NEW JERSEY.

DESIGN FOR A STAIR-CARPET FASTENER.

SPECIFICATION forming part of Design No. 20,499, dated February 3, 1891.

Application filed January 6, 1890. Serial No. 336,095. Term of patent 14 years.

To all whom it may concern:

Be it known that I, DAVID WALKER, a citizen of the United States, residing at Newark, in the county of Essex and State of New Jersey, have invented and produced a new and original Design for Stair-Carpet Buttons; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a front elevation of a portion of a stairway having the newly-designed stair-carpet button. Fig. 2 is a side elevation of the stair-carpet button in detail, and Fig. 3 is an enlarged front view of said stair-carpet button. Fig. 4 is a section taken on line *x*.

The leading feature of the design consists

in the stair-carpet button shaped as shown and described.

A indicates the upper part of the fastener, and B the lower end or edge, which is straight and turned or is at right angles to the part A. The upper edge of the part A is rounded at the corners. At the center of said part A is the perforation C, and at the opposite sides of said perforation the face of the plate is ornamented.

What I claim is—

The design for a stair-carpet fastener, as shown and described.

In testimony that I claim the foregoing I have hereunto set my hand this 3d day of January, 1890.

DAVID WALKER.
